(57) **CLAIM**

The design for the clog with rocker bottom, as shown.

DESCRIPTION

FIG. 1 is a top view of a clog with rocker bottom, showing my new design.

FIG. 2 is a bottom view thereof;

FIG. 3 is a left side view thereof;

FIG. 4 is a right side view thereof;

FIG. 5 is a front view thereof; and,

FIG. 6 is a rear view thereof.

The broken line showing of the butterfly detail on the mid-sole and sole is included for the purpose of illustrating environmental structure and forms no part of the claimed design.
